UNITED STATES PATENT OFFICE

155,065

DESIGN FOR A TIRE

Ray T. Bete, Cumberland, Md., assignor to The Kelly-Springfield Tire Company, Cumberland,
Md., a corporation of Maryland

Application August 20, 1948, Serial No. 148,226

Term of patent 14 years

(Cl. D90—20)

To all whom it may concern:

Be it known that I, Ray T. Bete, a citizen of the United States, residing at route #1, Cumberland, in the county of Allegany and State of Maryland, have invented a new, original, and ornamental Design for a Tire, of which the following is a specification, reference being had to the accompanying drawing, forming part thereof. The figure is a perspective view of a tire, showing my new design.

I claim:

The ornamental design for a tire, as shown.

RAY T. BETE.
